UNITED STATES PATENT OFFICE.

MATTHEW LITTLE, OF EAST SAGINAW, MICHIGAN, ASSIGNOR TO AMANDA M. STARKER, OF SAME PLACE.

DESIGN FOR A FLAT-IRON HEATER.

Specification forming part of Design No. 5,810, dated April 23, 1872.

To all whom it may concern:

Be it known that I, MATTHEW LITTLE, of East Saginaw, in the county of Saginaw and State of Michigan, have invented a new Design for a Flat-Iron Heater; and I do hereby declare the following to be a full, clear, and exact description of the same, reference being had to the accompanying drawing forming part of this specification, in which is represented a perspective view.

This invention relates to that class of flat-iron-heaters in which the utensil is constructed to fit upon the stove's holes like a common griddle; and the invention consists in an improved shape and configuration of such articles of manufacture, as I will now proceed to describe.

In the drawing, A is a flat cast-iron plate, provided with lugs to hold the bail, one of which is seen at a, with feet e e underneath, and with an ornamental bead, r, extending around its upper edge, as shown. B B are two flat-iron receptacles, arranged side by

side, each provided with a slotted cover, b, as shown, said covers likewise having an ornamental bead, r', around their edges. The front walls of the receptacles B B are extended into a kind of vertical lug, d, which is embraced by and pivoted to lugs m m cast upon the covers to form a hinged joint for them. The under side of the plate or griddle A is flat and smooth, except where the uniformity of its surface is broken by the feet e. A circular opening, covered by a small round griddle, S, having a bead, s, around its edge, may be provided between the front ends of the receptacles B B, as shown.

Having thus described my invention, what I claim as new, and desire to secure by Letters Patent, is—

The design for flat-iron heaters, substantially as herein described and shown.

MATTHEW LITTLE.
